UNITED STATES PATENT OFFICE.

HERMAN SCHLAICH, OF LONG ISLAND CITY, NEW YORK, ASSIGNOR TO MOTORMETER COMPANY, INC., OF LONG ISLAND CITY, NEW YORK, A CORPORATION OF NEW YORK.

DESIGN FOR A RADIATOR CAP.

Application filed April 13, 1923. Serial No. 5,805. Term of patent 14 years.

To all whom it may concern:

Be it known that I, HERMAN SCHLAICH, a citizen of the United States, residing in Long Island City, county of Queens, and State of New York, have invented a new, original, and ornamental Design for Radiator Cap, of which the following is a specification, reference being had to the accompanying drawing, forming a part thereof.

Figure 1 is a plan view of a radiator cap embodying my new design;

Figure 2 is a front elevation thereof; and

Figure 3 is a side elevation thereof.

The radiator cap comprises a body portion provided with oppositely extending arms. The salient feature of the invention consists in the provision of knobs or enlargements at the outer ends of the arms, and the provision of crystals in the faces of the enlargements.

I claim:

The ornamental design for a radiator cap substantially as shown and described.

HERMAN SCHLAICH.
